UNITED STATES PATENT OFFICE.

PEDRO MORA RICO, OF ARECIBO, PORTO RICO.

DESIGN FOR AN INKWELL.

Application filed May 18, 1923. Serial No. 6,209. Term of patent 14 years.

To all whom it may concern:

Be it known that I, PEDRO MORA RICO, a citizen of Arecibo, Porto Rico, residing at Arecibo, Porto Rico, have invented a new, original, and ornamental Design for an Inkwell, of which the following is a specification, reference being had to the accompanying drawings, forming a part hereof.

The figure is a perspective view of an inkwell showing my new design.

I claim:—

The ornamental design for an inkwell as shown.

PEDRO MORA RICO.
